DRIPLESS SAUCER

John A. Roehrig, 311 Field Club Ridge Road,
Pittsburgh, Pa.

Filed Feb. 1, 1962, Ser. No. 68,611

Term of patent 14 years

(Cl. D44—9)

Fig. 1.

Fig. 2.

Fig. 3.

Fig. 4.

FIG. 1 is a top, plan view of a dripless saucer showing my new design;

FIG. 2 is a cross-sectional view thereof taken along line 2—2 of FIG. 1;

FIG. 3 is a bottom view thereof; and,

FIG. 4 is a top, perspective view thereof.

I claim:

The ornamental design for a dripless saucer, substantially as shown.
